UNITED STATES PATENT OFFICE.

ALEXANDER W. WIMMER, OF CHICAGO, ILLINOIS.

ARTIFICIAL TOOTH.

1,070,219.

Specification of Letters Patent. Patented Aug. 12, 1913.

Application filed September 6, 1910. Serial No. 580,709.

To all whom it may concern:

Be it known that I, ALEXANDER W. WIMMER, a citizen of the United States, residing at Chicago, in the county of Cook and 5 State of Illinois, have invented certain new and useful Improvements in Artificial Teeth, of which the following is a full, clear, concise, and exact description, reference being had to the accompanying drawings forming a part of this specification.

My invention relates to an improved means for mounting artificial tooth crowns and facings, and has for its object to provide such a means that the crowns or facings when in place are securely held mechanically to the base or plate upon which they are mounted so that they cannot be accidentally removed.

In the past it has been common practice 20 to provide a backing plate from which projections extend into suitable openings in the tooth crowns or facings adapted to contain cement to secure them to the backing plate.

By my invention I provide individual 25 backing plates for the crowns or facings, and in addition to a projection extending from the individual backing plate into the crown or facing I employ a separate member for engaging the crown or facing in 30 such a manner as to positively lock it to the backing plate either with or without the use of cement, so that although it is usually preferable to employ cement to surround the locking members and fill all of 35 the interstices formed around them, the crown or facing is, nevertheless, securely locked to the backing plate even without the use of the cement. Furthermore, the locking member is preferably made removable so

40 that if the tooth becomes broken by accident, by cutting it away to uncover the locking member the latter may be readily removed, and the facing may then be removed from the backing plate without removing 45 the backing plate from the patient's mouth. The locking means may be employed in any one of a variety of ways, as will be explained below in connection with the drawings, in which—

50 Figure 1 is a sectional view through a tooth crown showing the backing plate in place and the locking member extending through the backing plate and also through the end of the projection formed upon the 55 backing plate; Fig. 2 is a view similar to Fig. 1, the only difference being that the

locking member does not extend through the projection formed on the backing plate.

Similar numerals refer to similar parts throughout the several views.

As shown in Fig. 1, the tooth crown 1 has formed therein a vertically extending opening or hole 2 intersected by a horizontally disposed opening or hole 3. An individual backing plate 4 is provided for the 60 crown 1 which has rigidly secured thereto a projection 5 adapted to fit into the opening 2. The projection 5 has formed through its lower end in alinement with the opening 3 a hole 6, through which a locking member or pin 7 may be inserted through a hole 8 in the backing plate 4 and through the opening 3 and the hole 6, thus serving when in place to securely lock the projection 5 from withdrawal, and thus to lock the back- 70 ing plate 4 in proper position. The construction described affords a ready means for temporarily securing the crown 1 to the backing plate 4 for the purposes of fitting so that the crown may be removed from the 80 backing plate to secure the backing plate to the mounting to be made, after which the crown may be secured to the backing plate permanently by placing a small amount of 85 cement in the openings 2 and 3, and, furthermore, this may be done without discomfort to the patient.

In the modification shown in Fig. 2, the locking pin 9 extends through the backing plate 4^a and into an opening or hole 11 90 formed in the crown 1^a, the opening or hole 11 being at a sufficient angle to the opening 2^a that when the locking pin 9 is in place the backing plate 4^a cannot be removed from the crown. This locking action, it is to be 95 observed, is the result of the projection 5^a and the pin 9 extending in different directions relatively to each other in the crown 1^a.

Thus my invention is adapted to use generally whether the crowns or facings be 100 molars, bicuspids, or incisors, and while the invention is particularly applicable to bridge work, it is not necessarily limited to this purpose but may be employed, if desired, in other connections in which it is 105 desirable to secure crowns or facings to mounting plates or bases. The locking pins shown and described above may, if desired, be slightly bent in order to retain them in the holes or openings formed therefor in the 110 crowns or facings, and in that modification in which the locking member or pin extends

through the projection secured to the tooth backing it is preferable that the pin be pointed to facilitate its entry into proper position. It is to be borne in mind that the 5 backing plates may be made commercially in large quantities so that they are duplicates of each other, or, if necessary, that the workman may, in a special case, construct a backing plate having projections se- 10 cured to and extending therefrom in any particular manner that may be required. Furthermore, the angles that the projections and locking members make with each other and with the backing plates may be varied 15 to meet any conditions found in practice, the essential feature being that the locking member engage the crown or facing in such a manner that it either engages the tooth backing or the projection secured thereto, 20 or both, so that the crown or facing and the backing plate are rigidly held together me- chanically and prevented from displacement relatively to each other in any direction whether cement be employed or not. Any 25 of a large number of crowns or facings thus made may be readily secured to any desired individual backing plate, as a result of which the crown or facing selected may have the proper color and may be of proper con- 30 formation to match the other teeth in the mouth, and, further, a new tooth may read- ily be placed upon a mounting plate, if for any reason the original tooth is broken, without removing the mounting plate from 35 the mouth of the patient, since all that is necessary is to cut away the original crown or facing until the locking member is dis- 40 closed when the latter may be removed and the original crown or facing may then be removed from the projection secured to the mounting plate. This operation is facil- 45 itated by the direction in which the projec- tion secured to the backing plate extends, which, as shown, is generally downward or toward the biting surface of the crown or facing.

Thus, by my invention I secure a construction which may truly be said to be inter- changeable without sacrificing in any degree 50 permanence or rigidity of attachment of the crown or facing to the mounting plate.

While the crowns or facings may be made of any desired material suitable for the

purpose, they are generally constructed of porcelain in a manner well known in the art. 55

While I have shown my invention in the particular embodiment herein described, I do not, however, limit myself to these constructions, but desire to claim any equivalents that may suggest themselves to those 60 skilled in the art.

What I claim is:

1. In an artificial tooth, the combination of a tooth crown or facing having holes formed in its body portion at an angle to 65 each other, a backing plate having a prong rigidly connected thereto and extending therefrom to enter one of said holes, and a separate pin insertible through the back- 70 ing plate to enter the other of said holes and engage the body portion of the backing plate to lock it to the crown or facing.

2. In an artificial tooth, the combination of a tooth crown or facing having holes formed therein intersecting in the body of 75 the crown or facing, a backing plate having a prong rigidly secured thereto and extend- 80 ing therefrom to enter one of said holes, and a separate pin insertible through the backing plate to enter the other of said holes and engage said prong and the body portion of the backing plate to lock the back- 85 ing plate in position upon the crown or facing.

3. In an artificial tooth, the combination 85 of a tooth crown or facing having holes formed therein intersecting in the body of the crown or facing, a backing plate having a prong rigidly secured thereto and ex- 90 tends therefrom to enter one of said holes and extend beyond the other of said holes, and a separate pin insertible through said 95 backing plate to enter the other of said holes and conformed to simultaneously extend through an opening in said prong and to engage the body portion of said backing plate to lock the latter in position upon the crown or facing.

In witness whereof, I hereunto subscribe my name this 31st day of August, A. D., 100 1910.

ALEXANDER W. WIMMER.
